UNITED STATES PATENT OFFICE.

SILAS J. SAXON AND WILLIAM H. JAMES, OF COLFAX, WASHINGTON.

FENCE-POST.

SPECIFICATION forming part of Letters Patent No. 423,633, dated March 18, 1890.

Application filed July 15, 1889. Serial No. 317,529. (No model.)

To all whom it may concern:

Be it known that we, SILAS J. SAXON and WILLIAM H. JAMES, both of Colfax, in the county of Whitman and Territory of Washington, have invented a new and Improved Fence-Post, of which the following is a specification, reference being had to the annexed drawings, forming a part thereof, in which—

Figure 1 is a side elevation of our improved fence-post. Fig. 2 is a vertical transverse section. Fig. 3 is a horizontal section taken on line $x-x$ in Fig. 2. Fig. 4 is a horizontal section taken on line $y-y$ in Fig. 2, and Fig. 5 is a horizontal section taken on line $z-z$ in Fig. 2.

Similar letters of reference indicate corresponding parts in all the views.

The object of our invention is to provide a fence-post formed partly of iron and partly of wood, and constructed so that no water can settle in any portion of the post, so as to freeze or cause the decay of the wood or the corrosion of the iron.

Our invention consists in an iron foot-piece provided with a tubular extension securely fastened in the iron foot-piece, preferably by casting the iron around and within the tube, and in the combination, with the iron foot-piece provided with the tubular extension, of a wooden part driven down upon the tubular extension, all as hereinafter fully described, and pointed out in the claim.

The foot-piece A of the post is preferably made of cast-iron, the lower part being cross-shaped, as shown in Fig. 5, while the upper portion is in the same form with a cylindrical hub B. The said hub is cast within and

around a tube C, which projects above the upper end of the foot-piece, so as to receive the wooden portion D. Into the lower end of the wooden portion D is driven a ferrule or ring E, and the wooden part D is driven onto the tubular extension C, the ferrule or ring and the tubular extension being concentric. The ferrule E is designed to prevent the post from splitting and for compressing the wood, so as to prevent the absorption of moisture.

The foot-piece A is set in the ground in the same manner as an ordinary post, with its upper end even with the top of the ground or a short distance above the ground-level. The wooden part D of the post is driven down upon the tube C.

It is obvious that the tube C may be formed integrally with the foot-piece A. Therefore we do not confine ourselves to the exact construction herein described.

Having thus described our invention, we claim as new and desire to secure by Letters Patent—

An improved fence-post, consisting of a metallic foot-piece A, provided with the hub B, having the tubular extension C firmly secured thereto and projecting from its upper end, and the wooden upper portion D, driven onto the tubular extension, the post being firmly and permanently secured to the foot, substantially as herein shown and described.

SILAS J. SAXON.
WILLIAM H. JAMES.
